BOTTLE CLOSURE

Alvin M. Whitney, Bradford, Pa., assignor to
Celloseal Company, Bradford, Pa., a corpora-
tion of Pennsylvania

Application August 17, 1935, Serial No. 36,730

2 Claims. (Cl. 215—8)

This invention pertains to new and useful improvements in bottle closures or stoppers and has for one of its important objects to provide means for closing a bottle or other container in a manner to render tampering with the contents thereof without detection impossible.

Another very important object of the invention is to provide a closure of the character described of the type including a bushing fixed in the bottle neck and having mounted therein an indicator plug, together with novel means for releasably securing said indicator plug in position.

Other objects of the invention are to provide a bottle closure of the character set forth which will be comparatively simple in construction, strong, durable, highly efficient and reliable in use and which may be manufactured and applied at low cost.

All of the foregoing and still further objects and advantages of the invention will become apparent from a study of the following specification, taken in connection with the accompanying drawing wherein like characters of reference 25 designate corresponding parts throughout the several views, and wherein:—

Figure 1 is a view in vertical section through a bottle closure constructed in accordance with the present invention, showing the device 30 mounted in the neck of a bottle.

Figure 2 is a view substantially similar to Figure 1, but showing the device after the frangible seal has been broken and the indicator plug dislodged.

Figure 3 is a vertical sectional view, showing the invention before it is inserted in the bottle neck.

Figure 4 is a detail view in perspective of the indicator plug.

Referring now to the drawing in detail, it will be seen that the embodiment of the invention which has been illustrated comprises a bushing 1 which is adapted to be fixed in any suitable manner, as by cementing, in the neck 2 of a bottle 3. The lower portion of the bore 4 of the bushing 1 is counterbored, as at 5, in a manner to provide a shoulder 6. Mounted in the counterbore 5 and engaged with the shoulder 6 is a frangible disk or seal 7 of suitable material. Fixed in the counterbore 5, as by cementing, is a ring 8 which retains the disk 7 in position.

Inserted in the ring 8 from the lower end thereof is an indicator plug 9 of any suitable material, said indicator plug including a substantially flat, circular head 10. The lower portion of the bush-

ing 1 is reduced, as at 11, and mounted on this reduced portion is a retaining ring 12 of suitable compressible material, preferably cork. The ring 12 includes a thickened lower portion 13 which extends below the bushing 1 and in which the head 10 is engaged for releasably securing the indicator plug 9 in position. If desired, a suitable cap may be provided on the upper end of the bottle neck 2.

In use, if a cap of the usual type is mounted 10 on the bottle neck 2, said cap is, of course, removed. A suitable instrument is then inserted in the bore 4 of the bushing 1 and the frangible sealing disk 7 is broken, after which the indicator plug 9 is forced downwardly out of the 15 ring 12 into the body of the bottle. As the bushing 1 is permanently fixed in the bottle neck 2, it will be impossible to remove the indicator plug 9, the head 10 thereof being of greater diameter than the bore 4 and it will accordingly be readily 20 apparent, by reason of the fact that the indicator plug has been dislodged, if the bottle has been previously opened. When the closure is forced to its position in the bottle neck the ring 12 will be contracted about the head 10 in a 25 manner to firmly secure the indicator plug 9 in position. Further, the retaining ring 12 will be compressed when the closure is inserted in the bottle neck and said ring will function as a seal 30 to prevent the content of the bottle from contacting the cement between the bushing 1 and the bottle neck 2.

It is believed that the many advantages of a bottle closure constructed in accordance with the present invention will be readily understood, 35 and although a preferred embodiment of the device is as illustrated and described, it is to be understood that changes in the details of construction and in the combination and arrangement of parts may be resorted to which will fall 40 within the scope of the invention as claimed.

What is claimed is:—

1. A bottle closure comprising a bushing adapted to be fixed in the neck of a bottle, the lower portion of the bore of said bushing being counterbored, and providing an internal shoulder, the lower portion of said bushing further being externally reduced, a frangible sealing disk engaged with the shoulder, a retaining ring fixed in the counterbored portion of the bushing and engaged 45 with the sealing disk, an indicator plug removably mounted in the retaining ring, said indicator plug including a substantially flat, circular head engaged with the lower end of the retaining ring 50 and the bushing, and a ring of compressible, con- 55

tractible material mounted in the reduced lower portion of the bushing and encircling same and depending therefrom, the depending portion of the second named ring being internally thickened and extending beneath the bushing and engaged with the periphery of the head for frictionally securing the indicator plug in position in the first named ring.

5 2. A bottle closure comprising a bushing to be fixed by cementing in the neck of a bottle, the lower portion of the circumference of said bushing being reduced in diameter forming a shoulder thereon, an indicator plug removably mounted on

the bottom of said bushing, said indicator plug including a substantially flat circular head engaged with the lower end of the bushing, said plug extending some distance into and fitting snugly the bore of the bushing, an annular gasket 5 of compressible material mounted on the reduced portion of the bushing and encircling it and extending below the same and including a preformed internal flange engaging the periphery of the head for frictionally securing the indicator plug 10 in position at the bottom of the bushing.

ALVIN M. WHITNEY.
